UNITED STATES PATENT OFFICE.

ADOLPH F. RIETZEL, OF WESTERLY, RHODE ISLAND, ASSIGNOR TO LACHMAN MANUFACTURING COMPANY, OF NEW YORK, N. Y., A CORPORATION OF DELAWARE.

PAPER CONTAINER.

1,201,347.

Specification of Letters Patent. Patented Oct. 17, 1916.

Application filed December 3, 1913. Serial No. 804,338.

To all whom it may concern:

Be it known that I, ADOLPH F. RIETZEL, a citizen of the United States, and a resident of Westerly, in the county of Washington 5 and State of Rhode Island, have invented certain new and useful Improvements in Paper Containers, of which the following is a specification.

My present invention relates to non-metallic containers and particularly to the manner of and means for securing the heads to the body of such containers.

The invention is particularly useful as providing a means for holding in the heads 15 of containers made of paper or straw-board as in the past considerable difficulty has been experienced in attempting to secure the heads in this type of container when the fastener itself pierces the paper forming the 20 body proper.

The invention will be herein shown as applied to cylindrical forms of paper containers, it being understood that its application to this use is for the purpose of illustration only.

The object of this invention is to simplify and cheapen the cost of construction of this type of container with particular reference to the fastening means for securing the 30 heads to the body.

It is also the object to simplify the operation attendant upon fastening in the heads so that the cost of assembling the parts of the complete container will be reduced and 35 at the same time the heads will be efficiently and effectively held in place.

I am aware that it has heretofore been proposed to use in paper containers continuous stay rods or strips located on the 40 side or outside of the container and by means of which both heads are tied or secured to the body portion of the container, but I desire to avoid the use of such continuous stay members owing to the increased amount of 45 material necessary as well as the difficulty of assembling.

The invention consists in the improved construction of container and head fastening therefor hereinafter more particularly 50 described and then specified in the claims.

In the accompanying drawings, Figure 1 is a vertical central cross-section through a paper container embodying the present invention in one of its forms. Fig. 2 is an en-

larged section illustrating one of the head 55 securing devices. Fig. 3 is a central cross-section through a container embodying a modification of this invention. Fig. 4 is an enlarged section illustrating one corner of the form shown in Fig. 3. Fig. 5 is a cross- 60 section showing a modified form of head fastener in side elevation. Fig. 6 is a similar view showing a still further modification.

The body portion of the container is preferably made up of a plurality of layers of 65 paper superimposed on each other and adhered together. When the invention is applied to a keg or barrel the body portion is in the form of a cylinder 1 formed preferably by spinning layers or strips of paper 70 on a mandrel and securing them together by a suitable adhesive, the superimposed layers being pressed together whereby a very rigid wall of any desired thickness is attained. The particular manner of forming the paper 75 cylinder constituting the body portion of the container forms no part of the present invention as any suitably formed paper body may be employed.

A metal band or hoop 2 located at each 80 end of the cylinder 1 is provided with a lateral flange 3 which seats on the edge of the cylinder and protects the raw edge of the paper from becoming mutilated.

The heads for closing each end of the 85 cylinder may be of any desired construction but by preference comprise a paper disk 4 forming the main closure. The said paper disk is preferably made up of a plurality of superimposed layers of paper adhered to 90 each other, the disk being provided with an annular metal rim to which it may, if desired, be secured in any suitable manner as by the rivets or staples 5 disposed at intervals about the rim. The head rim preferably 95 has an inwardly projecting flange 6 which bears on the surface of the disk 4 and an outwardly projecting flange 7 in a different plane than the flange 6, said flange 7 being adapted to seat on the flange 3 on the 100 end of the cylinder.

Referring to Figs. 1 and 2, the heads are secured to the body 1 by a plurality of separate fasteners disposed at any desired intervals about the body 1. Each fastener preferably 105 comprises a U-shaped metallic strip which is passed laterally from the inside of the container through holes in the wall

thereof as indicated in dotted lines in Fig. 1. As will be noted the legs 8 of the fastener pass through holes in the cylinder 1 formed at a distance from each other and 5 the same are drawn through until the base 9 bears against the inner periphery of the cylinder. The legs 8 are then bent upward and brought together against the outer periphery of the cylinder, the free ends being bent 10 into hook form over the metal rim of the head. As shown the fasteners are preferably formed of flat material but any other cross-section may be employed as desired.

As shown in Fig. 5, the base of the U- 15 shaped fastener may be extended at 11 from one side and formed into a lateral flange 10 forming a seat for the inner surface of the head disk 4.

Referring to Figs. 3 and 4, the fastener 20 comprises a single metal strip 12 the one end of which bears against the inner periphery of the cylinder 1 and after being threaded through the wall of the cylinder the strip is bent up against the outer periphery 25 thereof and the free end bent or hooked over the rim of the head. 13 indicates an annular ring fitting within the cylinder 1 and provided with a flange 13' forming a seat for 30 the head disk 4. By preference the ring 13 and strips 12 are welded together as at 14 in any suitable manner.

In Fig. 6 the fastener is shown as a strip of wire 15 formed similarly to the strip 12 and provided with a wire ring 16 welded to 35 the inner end thereof and forming a seat for the disk 4.

It will be understood that the invention is not limited to the various forms as shown and described but various modifications and 40 equivalents thereof might be resorted to without departing from the spirit of the invention as expressed in the appended claims.

What I claim as my invention is:

1. In a container, a paper body, a head 45 therefor, a metal strip threaded through the wall of said body and lying against the inner wall thereof and means secured to said strip within said body and adapted to engage the inner surface of said head, the

outer end of said strip engaging said head 50 opposite said means.

2. In a container, a paper body, a head therefor having a metal rim adapted to seat on the end of said body, a U-shaped metal fastener threaded through the wall of said body, means secured to said fastener on the inside of said body and adapted to form a seat for said head and a flexible extension of said strip on the outside of said body adapted to engage the rim of said head 60 opposite said means.

3. In a container, a paper body, a head provided with a metal rim adapted to seat on the end of said body and a U-shaped fastener for said head, the legs of which 65 pass transversely through the wall of said body and the ends turned over the end of the body and engaging the rim of the head.

4. In a container, a paper body, a head provided with a metal rim adapted to seat 70 on the end of said body and a U-shaped fastener for said head, the legs of which pass transversely through said body at a distance from each other with the base of the U-shaped fastener bearing against the 75 inner walls of said body, the legs of said fastener being brought together on the outside of said body and the ends bent over and engaging the rim of said head.

5. In a container, a cylindrical body, a head therefor having a metal rim adapted to seat on the end of said body, and a fastener comprising two parallel sides passing transversely through separated holes in the wall 85 of said body and united by a member lying against the inner surface of the body, said sides being extended and brought together against the outer surface of the body and terminating in a hook engaging the rim of 90 said head.

Signed at Westerly in the county of Washington and State of Rhode Island this first day of December A. D. 1913.

ADOLPH F. RIETZEL.
